D. Pettibone,
Boring Gun Barrels;
Patented Feb. 12, 1814.

12. T. T. T. 1005
To all to whom these Presents shall come, greeting:
I certify, that the annexed are true Copies of the following
Specification on behalf of my self, concerning and referring to
the device of an improvement in boring, Hawkbill, Bolt & Rifle
Barrel, by an Auger, called the spiral Grove or twisted screw
Auger for which Daniel Pittman obtained a patent the 11th
day of February 1811.

I, James Monroe, Secretary
for the Department of State of the United States of
America, have signed these presents, and caused to
be affixed hereto, at the City of
Washington, this nineteenth day of March A.D. 1811
and the thirty ninth year of the Independence of
the said States.

James Monroe

To the honorable James Monroe Esq; Secretary of State of the
United States of America. — The petition of Daniel Pittman
of Philadelphia Esq; to the 11th. — The
said Inventor certifieth and affly to use in the year 1799
new and useful improvement in the manner of boring the
pistol or rifle barrel by means of peculiar constructed auger
or bit, called the spiral Grove or twisted screw Auger or bit
(See Specification) A model of the Auger and a printed de-
scription of his improvement were filed and deposited in the
Office of State (where in this city) in the months of January
and August in the year above mentioned.

Your petitioner is therefore desirous of obtaining an exclusive
privilege in his said invention and humbly prays that the same
may be granted according to law and be granted price for his said
invention as in duty bound with due prigr. Your most obdt
Philadelphia

31. March 1812

Specification. To all persons to whom these presents shall come. Daniel Pittibone aforesaid number twelve years going by.

Do it known that I Daniel Pittibone doth invent and apply to use in the year 1799— a new and useful improvement in the manner of boring musket, pistol or rifle barrels by an auger (called the Special groove or twisted screw auger.)

The invention of the special groove or twisted screw auger for the purpose of boring Musket, pistol, or rifle barrels, consists in the manner of making it; or the particular form or construction of the same; as also the mode of application.

First— These augers are made of the best fast as other good steel welded to a handle or shank of good iron or steel. Then they are forged hammered & twisted in a similar manner to the common screw auger, save by carpenters for boring wood excepting the plate is left thicker before it is twisted. The difference in the form of this improved auger from the common screw auger and for boring wood. are that the points or cutters are next to the shank; and that the auger is left twisted for boring iron than for boring wood.

The shank of the auger is long enough to put through the barrel and fasten to the socket of the machine that moves or turns the auger. The auger revolves about once per second and the points or cutters are placed against the iron that is to be bored from the inside of the barrel. By the force of application of one or more endless screws that revolve in a track of pegs attached to the carriage on which the barrel is fastened. These endless screws revolve very slowly so as to give time for the auger to cut all that is required.— My further improvement is the placing of the barrel perpendicular. The improved auger can be well applied if the barrel is placed horizontally. The size of the shank of the auger are about one eighth of an inch less than the same on another

Secondly it is of much consequence to file or make the point of the cutters flat in the front so as to give the ship a proper deviation into the grooves. I make use of several different sizes to have a barrel: the shank of the second auger, for about four or five inches from the cutter is just as large as the cutters of the first, and the shank of the third the same size as the cutters of the second &c &c &c.

Secondly — For convenience of repair I file a piece of cast or other good steel about one eighth of an inch square through the shank next to the twisted part to form points or cutters. Thirdly I have also made augers by forging and turning very smoothly, in a lathe a bolt or pin of good steel - six or seven inches long - It was then helded to a shank at one end and with one or two inches of the other I file through a piece of steel to form points or cutters. This piece of steel is secured in its place by a small screw entering the end on side of the bolt or pin. — And from the points or cutters — spiral grooves are cut to the end.

Fourth — In some instances I cause the barrel to revolve instead of the auger for the purpose of boring more straight and true. The twisted part of the auger is best to be from six inches long, — frequently repair the points or cutters of the twisted augers with a steel punch or set, by heating the auger to a red heat, and temper it again.

Fifth — I sometimes make these bolts or pins hollow from the cutters or points to the end. — So that the ship may pass off internally; instead of passing off in the spiral grooves on the outside. I also make bolts, pins, or hollow cylinders that screw together some what like the points of a common umbrella or clasp - but that when screwed together, the cutters or points are fastened in its place - the ship's or barge's passing off internally or externally as circumstances may require.

The advantages of the new Bristols.

Article Firstly. The screw auger is more easily avoided & kept in repair than any other; which will bear the straightest without injury to the barrel, and of an excellent size all the time.

Secondly. By putting removable cutters to the screw auger on to the other hand, they will last a long time, as usually the cutters will need repairing.

Thirdly. The placing the barrels perpendicular to the board is a great improvement as it will save much room in a building or factory. And one man can load two or three augers at once. Also the chips will drop out conveniently.

Fourthly. The end of screw which cuts is a matter of consequence to give a regular purpose against the cutters.

Fifthly. The making of hollow augers for the purpose of passing of the chips internally, is very convenient. But there is none of the simplicity of the twisted steel wire so easily made by a common workman & tools.

Witnesses.

Jacob Baker

City and County of Philadelphia

I. Personally appeared the above named Daniel Dettibone and being duly cautioned and solemnly called on the holy Evangelist of Alasity God; - That he verily believes himself to be the first inventor of the improved method of making augers or bolts for boring Musket, pistol, & Rifle barrels; as above specified and described. - And that he is a citizen of the United States of America.

Sig. and Daniel Dettibone

Done on the 31. day of March 1812 before me Jacob Baker Notary.

I declare on the truth. Mr. Thornton informed me that he had seen your Name in this Register previously to the 13th day of March 1814. Daniel Dettibone (1452 words)
